UNITED STATES PATENT OFFICE.

LILLIAN M. BENDER, OF SAN FRANCISCO, CALIFORNIA.

BUST-REDUCING BRASSIERE.

Application filed May 17, 1922. Serial No. 561,774.

To all whom it may concern:

Be it known that I, LILLIAN M. BENDER, a citizen of the United States, residing in the city and county of San Francisco and 5 State of California, have invented certain new and useful Improvements in Bust-Reducing Brassières, of which the following is a specification.

The present invention relates to that class 10 of ladies' underwaists intended to be worn for reducing the size of abnormally developed busts, while, at the same time, affording thereto a comfortably yielding support.

The object of the invention is to provide 15 a simple one-piece seamless underwaist of the character specified, constructed of sheet-rubber, or an equivalent elastic material, impervious to moisture, fitted to the form and supplied with the necessary means for its 20 proper securing and adjustment to the body.

With these and other ends in view, the invention consists of certain improvements and combination of parts, all of which will 25 be hereinafter more fully described, and the novel features more particularly set forth in the claims appended hereto.

In the accompanying drawings, forming a 30 part of this specification and in which like reference characters designate similar parts, throughout, Figure 1 is a view disclosing the brassière in position upon a figure.

Figure 2 is a front elevation, showing the 35 general form and seamless character of the waist.

Figure 3 is a rear elevation, showing the means provided for securing and adjustment of the brassière, when in place.

Referring more particularly to the drawings, 1 represents the elastic body portion of my brassière, 2 the bust cavities thereof, 3 rubberized fabric strips cemented to the edges of the back opening therein and to which are secured fabric strips 4 bearing 40 eyelets 5, 6 rubberized shoulder tabs cemented to reinforced sections 9 of the body portion, 7 fabric shoulder straps secured to said tabs, 8 means through which attachment may be made to a separate garment,

and 9' a reinforcement as applied to a particular section of the brassière.

The material constituting the body portion of the brassière is, preferably, of sheet rubber, from which "blanks" are cut and then formed over properly prepared molds 55 and "baked" to cause the form to retain shape received from mold.

Since it is found to be practically impossible to unite directly the eyelet-bearing fabric strips to the rubber body portion, 60 with any degree of permanancy, owing to the elasticity of the latter, a rubberized fabric is employed to connect the one with the other. Being rubberized, this fabric may be joined to the rubber body portion by either 65 cementing or vulcanizing, while other fabrics may be joined to it by any one of a number of means.

The efficacy of the brassière, as constituted, as a bust reducing medium is due, in 70 part, to a compression lowered circulation and a consequently lessened deposit of fatty tissue, and, in part, to tissue elimination through an induced and increased perspiration.

I claim:

1. A brassière comprising a body portion of sheet rubber the front portion thereof being molded to conform to and compress the bust of a person, the back portion thereof being provided with an opening, strips of rubberized fabric cemented to the opposed edges of the opening, fabric strips stitched to the rubberized fabric strips, said last named strips having eyelets therein.

2. A brassière comprising a body portion of sheet rubber, the front portion being adapted to conform to and compress the bust of a person, the back portion being formed with an opening extending vertically 90 the entire length thereof, the strips of rubberized fabric, non-weakening fastening means securing said strips to the edges of said opening, non-rubberized fabric strips secured to said first named strips, said last 95 named strips being provided with means whereby the edges of the opening may be brought together.

3. A brassière comprising a body portion of elastic, impervious to moisture, flexible material opening in the back, and adapted to conform to and compress the bust of the wearer, rubberized fabric strips cemented to the edges of the back opening, non-rubberized fabric strips having eyelets therein stitched

to the edges of the rubberized fabric strips, rubberized fabric tabs cemented to the upper edges of the body portion and non-rubberized fabric shoulder straps stitched to the tabs. ¹⁰

LILLIAN M. BENDER.
